US00D773511S

(12) **United States Design Patent** (10) **Patent No.:** **US D773,511 S**
Watson et al. (45) **Date of Patent:** **** Dec. 6, 2016**

(54) **DISPLAY SCREEN WITH GRAPHICAL USER INTERFACE**

21/431; H04N 21/4312; H04N 21/4314; H04N 21/4316

See application file for complete search history.

(71) Applicant: **Microsoft Corporation**, Redmond, WA (US)

(72) Inventors: **MacBeth Watson**, Redmond, WA (US); **Megan McMillan**, Woodinville, WA (US); **David Gardner**, Covington, WA (US); **Eric Hsia**, Seattle, WA (US)

(73) Assignee: **Microsoft Corporation**, Redmond, WA (US)

(**) Term: **15 Years**

(21) Appl. No.: **29/533,232**

(22) Filed: **Jul. 15, 2015**

(51) LOC (10) Cl. **14-04**

(52) U.S. Cl.

USPC **D14/486**

(57) **CLAIM**

The ornamental design for a display screen with graphical user interface, as shown and described.

DESCRIPTION

The FIGURE is a front view of a display screen with graphical user interface showing our new design.

The broken lines illustrate the remainder of the display screen and the remainder of the graphical user interface. None of the broken lines form part of the claimed design.

1 Claim, 1 Drawing Sheet
